2,369,092

MANUFACTURE OF DECORATIVE SURFACES

Henry E. Walter, Cloquet, Minn., assignor to
 Wood Conversion Company, Cloquet, Minn., a
 corporation of Delaware

Application July 20, 1938, Serial No. 220,355

2 Claims. (Cl. 92—48)

The present invention relates generally to marking temporarily plastic material in the process of manufacture to produce permanent markings. It has particular reference to the manufacture of fibrous felts, such as thick paper or artificial board.

The particular object of the present invention is to produce intaglio impressions not of a definite pattern, but of a characteristic appearance in non-repetitive form; and to provide a means for that end.

The invention will be described with particular reference to artificial board made from an aqueous slurry of fibers, but it is to be understood, and it will be pointed out, that it has other applications; and that the device of the invention, and the manner of using it may vary considerably. Having reference to the accompanying drawings, the invention will be illustrated and explained as it is applied in marking artificial board.

In the drawings:

Fig. 1 is a reproduction of a photographed picture of the surface of a wall board panel made by the present invention.

Fig. 2 is a diagrammatic representation of the marking means.

Fig. 3 is an edge view more or less diagrammatic, of the means of Fig. 2.

Fig. 4 is a longitudinal vertical section of a machine for continuously marking a continuously formed web of wallboard.

In order to attain a non-repetitive pattern the impression means is multiple and each element is in part mobile and free to assume different positions. Each element is also in part constrained and fixed in part with respect to a carrier of the multiple elements, so that there is produced by the constraint, a general identity, or individual character in the design, and a pleasing non-repetitive variation in the design produced by the mobile parts.

This is readily accomplished where a design of lines is desired, by having one or more carrier elements to which a multiplicity of strands or cords is attached at points spaced along the strands or cords; each strand or cord being loose relative to the carrier between each two adjacent spaced points of attachment to the carrier, the looseness being due both to non-attachment to the carrier and to the cord or strand having a length greater than the distance measured in the carrier between adjacent points of attachment. Therefore, when the carrier is taut, the strands are not taut, and they may assume any free position between the points of attachment.

The carrier is one or more elements adapted to be pulled taut in one direction. The carrier is preferably a sheet backing. It may be a felt, or canvas, or rigid or flexible net, or merely be a plurality of parallel cords without lateral connections between them in the area used for impressions. The latter arrangement, and a coarse netting, can therefore be used in a taut position with varying widths coverable by the same backing, giving a finer or coarser pattern in the lateral direction.

The strands or cords may be of fiber, such as rope, yarn or cord, or flexible wire or even rubber, and the latter may be smooth or marked, as desired. One strand, for example, may be attached to the backing at evenly spaced intervals in a straight line, running generally in the direction of the taut backing, or definitely angular to it, or in some irregular line. Other cords may have an exactly similar attachment, and all points of attachment be arranged in parallel lines across the taut length. Some may be staggered with respect to others. There may be strands across the taut length. These may be attached to the backing, or even be a part of the backing, as where a coarse net is used, and not stretched laterally when it is pulled taut lengthwise.

In other words, the character of the backing, or the manner in which it is applied as a carrier, coupled with the pattern of the fixed points of attachment, is the means to provide the desired character or general identity to a design. The manner in which the cords or strands are free to assume different positions, is the cause of variation in the pattern, and the particular cause of a non-repetitive pattern.

In order to avoid showing the many possible variations of the pattern, one illustrative form is selected, which gives a pleasing effect. In Fig. 2 there is shown a carrier which is a coarse net having a warp of heavy cords 10 adapted to be pulled taut to apply the carrier. Lighter weight transverse cords 11 are shown and at the intersections, any type of connection may be applied. When the net is expanded laterally to the full permissible width the transverse cords 11 will be taut, but for the purpose of illustration the net is shown slightly contracted laterally with a taut warp, whereby the transverse cords between the warp cords are irregularly arranged, and will make a variable design where they may penetrate the plastic material.

In Fig. 3 the diagrammatic block 12 indicates the edge of a carrier, and the single cord 13 thereon is representative of the strands which make

the design. Cord 13 is shown with three spaced attachments 14, 15 and 16, of which 15 and 16 are points, while 14 is a length of cord 13 secured to carrier 12. On any carrier, the places of attachment, like 14 or 15, may be repetitive or non-repetitive in design. The repetitive design for attachment may be such as to give always an individual characteristic to the resulting effect, with uncontrollable variations from the loose parts. In Fig. 2, the strands or cords are designated 17, and the places of attachment are points 18, in a row across or otherwise disposed on the backing. Each strand 17 is shown with its series of spaced attachments alined, not in a straight line, but in staggered relation, with looseness of strand between adjacent points in the taut carrier. Thus the strands may fall into wavy lines generally, but not mathematically or regularly, or repeatedly. From the foregoing it is obvious how the arrangement may be varied.

Where the carrier or backing is a flexible sheet relatively closed, like canvas, the strands are located on the impressing surface thereof. But where the carrier is more open, like a net, the strands may be on either side thereof, or both sides. Where the strands cross the net on the non-impressing side, the cords of the net may be utilized as part of the impression means. Likewise, the cords of the net may function where they are exposed on the impression side, between strands 17.

Fig. 4 represents one way in which such an impression fabric may be used in a continuous machine for making artificial board.

Numeral 20 indicates a Fourdrinier or forming wire or screen on which the wet fiber mat 21 is formed and on which it is yet quite plastic through the retention of water. This screen runs along over supporting rolls 22, then through a set of heavier press rolls 23 and 24, lighter press rolls 26 and 27, heavy squeeze rolls 28 and 29, and a second set of squeeze rolls 30 and 31. The wire returns over the lower roll 30, and the moist or damp fiber layer 32 is quite self-supporting, and ready to be dried. As the plastic mat 21 enters these rolls it receives on its top a stretch of an endless impression carrier 33 according to this invention, and an endless thick felt 34 which takes up water squeezed out. Rolls 31, 35 and 36 carry the felt 34. Rolls 31, 35, 37, 38, 39, 40 and 41 carry the impression blanket. Roll 39 depresses the blanket into washing tank 42, so that it may be cleaned of adherent fiber to assure clean impressions. A press roll 43 over roll 38 squeezes excess water out before the blanket is used again. At the roll 31 the loose impression material is removed from the permanent impressions now set in the mat. Then the board goes to drier 44.

In the manufacture of board as described in the machine of Fig. 4, it is obvious that the felt 34 may itself provide the carrier generally described without departing from the invention. A separate carrier is preferred for many reasons. It is also to be understood that in many board-making machines there is used a top-wire as well as the lower forming-wire. The top-wire also may be used as the carrier for the present invention.

It is further to be understood that I have described the invention in terms of "carrier" and "loose elements" in order to explain clearly the different and specific functions. But it is to be understood that the elements and functions may

be merged without departing from the spirit and scope of the invention. For example, referring to Fig. 2, I have described a taut set of strands 10, and a loose set of strands 17. Both sets may be identical strands. One or more strands may belong to set 10 at one part of the structure to function as a carrier, and belong to set 17 at another part of the structure to function as a mobile element. It is therefore to be understood that the invention in its broadest aspect provides a marking structure which as a whole is capable of being pulled in a taut relation to fix the position of the fixations of the mobile elements, so as to present mobile elements for self-positioning. The pattern designed, and the questions of construction with ease and economy determine the exact construction of the device.

It is of course to be understood that a single length (not an endless belt) of impression blanket, may be used where a non-continuous process is used. For example, it may be used in the press shown in U. S. Ziska Patent No. 1,690,152, which is used in an intermittent operation in making artificial board, serving at the same place as the press rolls above described.

Any board made by use of the above described marking device has a pleasing effect by reason of its non-repetitive pattern and other factors. The depth of depressions in the design are such as to cause visual shadows, and for this purpose should not be less than 0.04 inch. The surface of the board presents the major portion of the high spots flattened to the same plane parallel with the opposite face of the board to give a uniform caliper to the board. These flattened high spots give high lights to contrast with said shadows. It is of course to be understood that the same method and impression material may be used in cement, plasterboard, gypsum board, and other temporarily plastic body materials having a decorative surface. These are impressed while plastic, partially set to hold the impressions, and then completely set after removal of the impression-making means.

The invention obviously is not limited to surfacing fiber boards, but may be used on any plastic material. Therefore the invention is broadly defined in the appended claims.

I claim:

1. An impression device for making intaglio designs in a plastic mass, comprising an open network carrier, and a multiplicity of strands carried by and over a face of said carrier, the arrangement of various of the strands being characterized along the length of a strand by more than two spaced attachments to and along a dimension of the carrier, and relatively to the carrier by mobility and looseness between adjacent attachments when the carrier is applied to make an impression.

2. An impression device for making intaglio designs in a plastic mass, comprising a flexible network carrier adapted to be pulled taut in at least one direction, and a multiplicity of strands carried by and over a face of said carrier, the arrangement of various of the strands being characterized along the length of a strand by more than two spaced attachments to and along a dimension of the carrier, and relatively to the carrier by mobility and looseness between adjacent attachments when the carrier is taut in said direction.

HENRY E. WALTER.
